DOWNDRAFT CARBURETOR

George M. Holley, Grosse Pointe, Mich., assignor
to Geo. M. and Earl Holley Engineering, De-
troit, Mich., a trust

Application September 15, 1934, Serial No. 744,160

17 Claims. (Cl. 261—41)

This invention relates to plain tube gasoline carburetors as distinguished from variable venturi and air valve carburetors as used with automobile engines in which the maximum performance is required with the minimum fuel consumption. Generally speaking, all such carburetors now provide a road load mixture ratio about 10% leaner than the wide open throttle ratio and temporarily provide an extra fuel supply driving acceleration. Otherwise the mixture ratio is remarkably uniform.

One of the problems with these plain tube carburetors is to bridge the inevitable gap from the throttle running when a small idling carburetor discharges fuel into the mixture outlet adjacent to and in advance of the throttle and when the throttle is wide open and a rich mixture is discharged into the Venturi throat of the mixture chamber.

The nozzle construction commonly used is one in which a master regulating nozzle controls the low and high speed fuel supply and a fuel pump discharges fuel through a separate nozzle to bridge the gap when the fuel ceases to discharge from the low speed fuel nozzle and is not yet discharging from the main fuel nozzle.

Another big problem is to obtain distribution with a downdraft carburetor. When updraft carburetors were in use (3½ years ago) there was quite a distance from the carburetor flange to the point in the manifold where the mixture divides and the mixture had a straight flow for this distance. Now, with the downdraft carburetor there is no room for such a distance, as when the air cleaner is installed then the carburetor and inlet manifold are designed as close together as possible and with the usual butterfly throttle the mixture is not distributed uniformly between the various cylinders. This is especially true if the throttle shaft is not located parallel to the axis of the crankshaft and a location at right angles to the axis of the crankshaft is the most convenient location for the throttle controls.

The object of this invention is, therefore, to solve these problems with a plain tube carburetor of compact form (having the greatest capacity for a given size). Specifically, my solution is to locate a butterfly throttle in the throat of the venturi of the mixing chamber into which the low speed nozzle also discharges so that the low speed nozzle remains in operation until the high speed nozzle supplies the major portion of the fuel so that the transitions from low and high speed may be made smoothly without disturbing the mixture ratio unduly.

The solution is complicated by the necessity of including a power jet; an accelerating pump; and priming means, without appreciably increasing the dimension of the carburetor.

The distance from the butterfly throttle to the mixture outlet gives the best possible distribution in the dimensions available. With the orthodox construction the throttle being located in the mixture outlet, this distance is not available for enabling the air stream to straighten itself out and for the mixture to distribute itself uniformly in the air stream. I have also discovered that by locating the throttle in the Venturi throat that I can get excellent performance with an unusually large throat diameter.

By arranging a small venturi to discharge against the upstream face of this throttle, I obtain the effect of a variable venturi.

Fig. 12 shows a diagrammatic illustration of the principle of operation without the accelerating or economy means.

Fig. 13 shows diagrammatically the increase in Venturi depression obtainable by the novel construction.

Fig. 14 illustrates the method of measuring the depression in the throat of the venturi of the novel construction.

Fig. 15 shows the method of measuring the depression in a venturi of an orthodox carburetor. Fig. 16 shows diagrammatically the essential fuel and air passages with the exception of the priming means which constitutes a separate invention.

Description

In Fig. 12, 10 is the air entrance leading to a Venturi tube in the throat 11 of which a butterfly throttle 12 is located mounted on a throttle shaft 13. Discharging into the Venturi throat 11 on the atmospheric side of 12 is a smaller venturi 14. Into the throat of 14 a nozzle 16 discharges and is fed from two sources as follows:

(a) An air vented well 18 into which the restricted fuel outlet 62 feeds from the float chamber 17.

(b) A non-air vented nozzle 60 which normally is in free communication with the float chamber 17 through the passage 61 (Fig. 4).

This combination of a plain nozzle with an air vented nozzle is a well known nozzle construction which gives a substantially constant mixture ratio and also permits slight departures from a constant mixture ratio so that the economy at all speeds can be positively and easily controlled.

Briefly the nozzle 60 tends to become richer at high air flows; the air vented well 18 tends to become leaner, hence either tendency can be arranged to overcome the other as desired. The low speed fuel is drawn from the lower portions of the air Venturi well 18 thru the passage 72-73 which discharges into the chamber 74 where a little air is mixed with it and then the air and fuel discharges thru 19; as the throttle 12 opens the nozzle 16 also discharges. Then as the depression in 14 increases the fuel from 62 flows both out of 19-19' and out of 16. Finally at extremely high speeds the depression in the throat of 14 is such that all the fuel that enters 18 at 62 flows up out of 16 and none flows thru 72-73 to 19, but normally this does not take place.

In the Figures 1 to 11, 10 is the air entrance leading to a Venturi throat 11 in which is located a butterfly throttle 12 mounted on a throttle 13. This venturi discharges into a mixture outlet 30 into which also discharges the low speed air passage 22 and the priming mixture passage 31 (Fig. 3). A small venturi 13 discharges at 11 on the atmospheric side of the throttle 12.

In Figure 6, 18 is an air vented fuel well having an outlet 16 discharging into 14 and a restricted fuel entrance 62 located in the bottom of the float chamber 17 and connected with 18 through 66. An air entrance 63 having a restricted plug 64 supplies the air from 10 for the well 18. A tubular perforated piece 65 which carries the outlet 16 is threaded into the well 18 above the point where the fuel passage 66 enters. Another concentric tube 66, which communicates directly with the accelerating pump shown in Fig. 4 through the fuel passage 67 (see Figs. 1, 4, 6 and 10) is mounted inside the perforated tube 65 66 but is separate therefrom.

The perforated sleeve 65 divides the air vented well 18 into two parts; an inner one which discharges through 16 and an outer one which is connected with the atmosphere at 64 in its upper end. At its lower end a low speed fuel outlet 68 is provided, which is connected with the fuel passages 69, 71, 72, 73 and 74 to the low speed fuel outlet 19-19' as follows:

Fuel for the low speed nozzle 19-19' (shown in Fig. 5) is drawn up the passages 69 to the small

chamber 70 where air is admitted from 10 through 29, past a low speed adjusting screw 98. The flow of fuel into 10 is regulated by a restriction 71 and the mixed fuel and air from the chamber 70 enters the mixture chamber 11 through the double low speed fuel outlets 19-19' travelling through the passage 72 and 73 to the small chamber 74. The double outlet 19-19' is located adjacent to and on the engine side of the throttle 12 so that as the throttle opens the flow through 19' increases and its flow is added to that flowing thru the upper orifice 19.

The power jet 95 (see Figs. 1 and 6) obtains its supply of fuel direct from the float chamber 17 through the passage 76 and the restricted opening 75 (see Figs. 7, 8 and 9) in which Fig. 7 shows the throttle $\frac{1}{2}$ open, Fig. 8 shows the throttle closed and Fig. 9 shows the throttle wide open. The nozzle is connected through a passage 61 with a small chamber 78 (see Figs. 1, 6, 7, 8 and 9). Into an air vented well 77 a tube 84 dips which discharges into the small chamber 78 which communicates through the restricted passage 61 with the power jet 95 which discharges into the mixing chamber (which is the throat 11) on the atmospheric side of the throttle 12.

In the throttle position shown in Fig. 8, the maximum economy is obtained, a passage 79 being connected to the air entrance 10 and with the chamber 78 through the passage 81-80-82. 80 is a passage drilled in the throttle shaft 13 which acts as a valve controlled by the throttle 13. When the throttle is closed (Fig. 8) the throttle valve 8 puts the air entrance 10 in communication with the chamber 78 through the inclined passage 82.

In the position shown in Fig. 7, the flow from 81 to 82 is obstructed by the partial closing of 80 and air flows down from 78 to the inclined passage 83 which leads into the upper portion of 40 the well 77. This gives an increased fuel flow. In the Fig. 9 the passage 81 is completely blocked by the throttle 13 and maximum fuel flow is secured corresponding to the maximum power requirements. These arrangements for controlling 45 the mixture ratio with throttle wide open correspond to Patent No. 1,825,788.

Acceleration

The accelerating fuel pump shown in Fig. 4 gets its fuel supply direct from the float chamber 17, through the gravity controlled non-return valve 85 and discharges through the passage 67 which in its turn discharges into the fuel nozzle 16 through the small central nozzle 66 (Fig. 1). This pump is operated by the throttle shaft 13 to which is bolted a lever 86, a link 87 connecting 86 with the piston rod 88 provided with a ball end 89 which engages with the walls 90 (forming the shallow cup 91) which project 60 from the piston 92. A spring 93 provides the accelerating driving power when the ball ended rod 89 is suddenly depressed by opening the throttle 12 and the piston 92 is released from the connection with the throttle 12. The travel of the ball end 89 is beyond that of the clearance provided in the cup 91 so that if the throttle is suddenly opened then 89 will strike the back of the piston 92.

Starting means

The starting means comprise a starting fuel nozzle 32 fed from the float chamber 17 (see Fig. 3) and discharging into the well 33, vented by means of the tube 34 which has a small hole 75

at its upper end to break the siphoning action which would otherwise take place. This tube communicates through 35 with 36 which is in free communication with the air entrance 10.

5 A passage 37 conveys fuel and air to the vertical passage 38 down which it flows to connect thru 39 into the chamber 28 whence the fuel is discharged thru 31 into the mixture outlet 30. A starting valve 40 with a stop 41 which engages 10 with the carburetor casting 40 controls both the mixture outlet from 28 into the priming passage 31 and the entrance of the fuel from the passage 39 into the air chamber 28. A rod 54 mounted in 40 engages with a disc valve 53 with 15 openings 52. A valve 26 is mounted on 53 so as to close the openings 52 by its valve seat 27, a pilot 56 on 53 holding these valves concentric with each other. 26 is made in the form of a piston reciprocating in the cylinder 25 and is 20 operated by means of vacuum introduced through the passage 24 which connects with the passage 22 which communicates with the mixture outlet 30. An opening 57 admits atmospheric air beneath the valve 26 to raise it. Cooperating with 25 the starting means is the low speed air supply passage 22 which is controlled by the adjustable screw 23 (Fig. 11).

This passage supplies air to mingle with the fuel discharged at the lip of throttle 12 out of 30 the opening 19' and thus makes an explosive mixture in 30 when the throttle valve 12 is completely closed. The screw 23 (Fig. 11) thus corresponds to the throttle stop ordinarily used with carburetors, the adjustment of which determines 35 the idling speed.

This novel low speed and starting control is the subject of another patent application.

Operation

40 The carburetor is started with the throttle completely closed. A very rich mixture is thus drawn from the float chamber 17 out of the well 33 (Fig. 3) down the passage 37-38 together with the air drawn through 34. This fuel and 45 air discharges through 39 and flows through 31 into the mixture outlet 30. The moment the engine begins to fire the vacuum in the inlet manifold acting through 30 is communicated thru the passage 22 to the passage 24 and the 50 piston rises under the action of atmospheric air acting on the outside of the valve 26 thereby uncovering the openings 52 in the plate 53 and thereby permitting air to flow into the chamber 28. Thermostatic means not shown may be provided for moving the piston 40 which first raises 55 the valve 53 giving a fast idle immediately and gradually cuts off the priming fuel of 39 and the outlet passage 31. This is the subject of co-pending application Serial #616,278 and U. S. 60 Patent 1,998,581.

The low speed fuel supply of the engine is then obtained through the double fuel outlets 19-19'. This fuel flows from the float chamber 17 (Figs. 5 and 6) thru the restriction 62 up the passage 65 66 across the passage 68, up the passage 69, thru the restriction 71, into the chamber 70, where air is admitted past the regulating idle screw 99. The rich mixture flows across 72 and 73 into the chamber 74 out of which it flows 70 through 19 into the venturi 11 adjacent to and just in advance of the upstream lip of the throttle 12.

The idling adjustment is made by regulating the fuel supply by the screw 23 (Fig. 11) and the 75 air supply by the screw 99 (Fig. 5). 99 is screwed

in to give a richer mixture and 23 is screwed out to give a higher speed.

If the throttle is opened, the nozzles 19-19' increase the fuel flow in a well known manner. Meanwhile the fuel level in 18 is thereby slightly 5 lowered to prevent the premature discharge of fuel from 16 into 14. Later as the throttle 12 opens, fuel flows from 17 thru 66 into the well 18 from whence it is displaced by air flowing down 64 and through the perforated tube 65. 10 This mixture of fuel and air flows thru 16 into the throat of the small venturi 14. At the same time fuel flows from the pump chamber (shown in Fig. 4) flowing past the check valve 85 which offers no restriction (when the pump is not operating) and out of the fuel passage 67 which communicates with the high speed fuel nozzle 60 (see Fig. 6). This fuel discharges thru the outlet nozzle 60. If the throttle is moved quickly, the piston 92 discharges an extra flow 20 thru 67 and at the same time closes the check valve 85. Meanwhile the throttle shaft 13 has been rotating so as to move the passage 80 out of line with the passage 81 (see Fig. 8) and to provide the extra fuel required when running 25 with a wide open throttle.

In Fig. 7 the passage is sufficiently obstructed so that air flows from 79 down 83 and displaces the fuel in the well 77. This fuel being discharged thru the opening 61 which discharges 30 fuel into the throat of the venturi 11 thru the nozzle 85. This hole 80 is drilled in the shaft 13 at such an angle that the fuel flow thru 61 does not become appreciable until the throttle is opened beyond the normal economical running 35 condition of the throttle. In other words, the throttle is opened for power when economy is no longer of primary importance. The fuel nozzle 95 is commonly referred to as a power jet. Fuel for the well 79 is obtained directly from the float 40 chamber 17 thru the restriction 75. When the throttle is wide open the passage 80 completely obstructs the passage 81.

It will be noted that the mixture is formed by fuel issuing into 11 on both sides of the throttle 45 12 and that the distance from 13 to the flange is much greater than is commercially possible when the throttle 12 is located in the mixture outlet 30 and instead of in the throat 11 of the venturi 10-30. This distance is a vital factor in facilitating the desired uniform distribution of the fuel on the air stream which determines the ultimate distribution of the mixture to the engine cylinders.

Figures 13, 14 and 15 illustrate diagrammatically the difference between the applicant's construction, Figure 14, and the prior art (illustrated in Figure 15). Both the curves in Figure 13 represent the vacuum obtained at the throat of the smaller of the two venturis, 14 and 14'. The upper curve carries also the corresponding throttle portion required at normal operation running on a level boulevard to create the manifold vacuum against which the depression in the throat of the smaller venturi is plotted. In both cases the idling vacuum at 23° throttle is 18" of mercury. At 23° throttle position, that is, when idling, there is no measurable depression in the throat of either of the two smaller venturis 14 and 14'. Now 90° corresponds to 70 wide-open throttle, therefore, 90° minus 23° equals 67° constitutes the movement to wide-open throttle position. The curves are plotted just short of $\frac{3}{4}$ opening corresponding to 74.7° throttle position. At this position the manifold 75

vacuum has fallen to just over 2" of mercury when running on a level boulevard and the depression in the small venturi 14 of Figure 14 has now risen to 47" of water, but the curve is flattening out and has practically ceased to rise (upper curve).

In the case of the orthodox carburetor shown in Figure 15, the depression in 14' has only risen to 33" of water (lower curve), but this depression is rapidly rising so that at wide-open throttle 90°, the two curves will approach each other very closely or most probably actually meet. This is because the net throat areas of the two carburetors were selected so as to be the same, 15 hence the velocities of air at wide-open throttle are substantially the same for substantially the same cubic feet per minute flow. The reason for the marked difference between the two curves at part throttle is that by reason of the location 20 of the throttle in the embodiment shown in Figure 14 in the throat 11 of the main venturi, it follows that when partly closed, most of the air is guided by the throttle so as to flow through the portion of the passage on the right side of 25 the throttle 12 and hence the velocity of the air on that side increases and the pressure in 14 drops due to the diversion of the air stream over the mouth of the smaller venturi.

What I claim is:

30. 1. In a carburetor the combination of a mixture chamber of venturi form having a restricted throat, a throttle located in the throat, a smaller venturi having its axis inclined to the axis of the main venturi and discharging into the throat 35 of the main venturi against said throttle valve and on the atmospheric side thereof whereby the outlet from the smaller venturi is restricted when the throttle is in its closed position, a constant level fuel supply chamber, an air vented fuel 40 well fed therefrom, an air and fuel outlet from said well discharging into the throat of said smaller venturi.

45. 2. In a carburetor for an internal combustion engine, a mixing chamber of the Venturi form having a restricted throat, a butterfly throttle valve therein, a fuel supply chamber, a fuel outlet therefrom, an air vented reservoir into which said outlet discharges, an outlet from the upper part of said reservoir discharging into 50 said throat on the atmospheric side of and against said throttle, said throttle being located so as to divert when partly closed the main air flow past said outlet, a low speed fuel outlet so located in said venturi as to discharge against 55 the opposite side of said throttle and so as to be progressively subjected to the engine suction as the throttle is moved from the closed position, a passage connecting said low speed fuel outlet with an outlet from the lower portion of 60 said reservoir.

65. 3. In a carburetor for an internal combustion engine, a mixing chamber having a restricted throat, a butterfly throttle valve located in the throat thereof, a fuel supply chamber, a fuel outlet therefrom discharging into an air vented reservoir associated therewith, an outlet from the upper part of said reservoir discharging into 70 said mixing chamber against said throttle on the atmospheric side thereof, said throttle being located so as to divert when partly closed the main air flow past said outlet, a second outlet therefrom discharging into said mixing chamber against said throttle on the engine side 75 thereof and so located as to be progressively

subjected to the engine suction by the throttle as the throttle is moved from its closed position.

4. In a carburetor a Venturi tube having a restricted throat, a throttle valve therein, a smaller venturi having its axis inclined to the axis of the main venturi and discharging into the throat of the main venturi on the atmospheric side of and adjacent to said throttle valve, a constant level fuel supply chamber, an air vented fuel well fed therefrom, an air and fuel outlet from said well discharging into the throat of said smaller venturi, an unvented fuel nozzle also fed from said fuel chamber and also discharging into the throat of said small venturi. 15

5. In a carburetor a main mixing tube of Venturi form having a restricted throat, a throttle valve therein, a smaller mixing tube having its axis inclined to the axis of the main mixing tube and discharging into the throat of said main mixing tube on the atmospheric side of and adjacent to said throttle whereby the outlet from the smaller tube is restricted when the throttle is in its closed position, a constant level fuel supply chamber, an air vented fuel well fed 20 therefrom, an air and fuel outlet from the upper part of said well discharging into said restricted throat on the atmospheric side of and adjacent to said throttle, through said smaller mixing tube. 25

30. 6. A downdraft carburetor for an internal combustion engine having a mixture chamber of Venturi form therefor having a throat, a butterfly throttle mounted therein, means for discharging low speed fuel against the downstream half of said butterfly throttle on the engine side thereof and means adjacent to said throttle for discharging high speed fuel directly against the upstream half of said throttle and on the atmospheric side thereof, said throttle being so located that it diverts when partly closed the main air flow past said high speed fuel discharge means. 40

35. 7. A carburetor for an internal combustion engine having a mixture chamber of Venturi form, a throat therefor having a butterfly throttle mounted therein, means for discharging low speed fuel against the downstream half of said butterfly throttle and on the engine side thereof and means adjacent to said throttle for discharging high speed fuel directly against the upstream half of said throttle and on the atmospheric side thereof, said throttle being so located that it diverts when partly closed the main air flow past said high speed fuel discharge means. 50

45. 8. A downdraft carburetor for an internal combustion engine comprising a downdraft mixing chamber of Venturi form having a restricted throat, a throttle valve therein, a mixture outlet leading therefrom, means adjacent to said throttle for discharging high speed fuel into said mixing chamber adjacent to and above said throttle, means for discharging low speed fuel into said mixing chamber adjacent to and below said throttle so as to be progressively subjected to the suction of the engine as the throttle is opened, said throttle being so located that it diverts when partly closed the main air flow past said high speed fuel discharge means. 65

55. 9. A downdraft carburetor as set forth in claim 8, said throttle being a butterfly throttle. 70

60. 10. A downdraft carburetor as set forth in claim 8, in which the means for discharging high speed fuel into said mixing chamber consists of a small venturi discharging into said mixing 75

chamber adjacent to and above said throttle and air and fuel supply means for said small venturi.

11. A downdraft carburetor as in claim 8 in which the means for discharging high and low speed fuels into said mixing chamber includes a constant level fuel supply chamber, an air vented fuel reservoir associated therewith, a high speed fuel outlet from the upper part of said reservoir and a low speed fuel outlet from the lower part thereof.

12. A downdraft carburetor as set forth in claim 8, in which the means for discharging high speed fuel into said mixing chamber includes a small venturi discharging into said mixing chamber above said throttle, a constant level fuel supply chamber, an air vented fuel reservoir associated therewith, a high speed fuel outlet from the upper part of said reservoir discharging into the throat of said small venturi and an additional high speed fuel nozzle independent of said air vented reservoir but fed from said constant level fuel supply chamber and also discharging into the throat of said small venturi.

13. A downdraft carburetor as set forth in claim 8, in which the means for discharging high and low speed fuel into said mixing chamber includes a small venturi discharging into said mixing chamber above said throttle, a constant level fuel supply chamber, an air vented fuel reservoir associated therewith, a high speed fuel outlet from the upper part of said reservoir discharging into the throat of said small venturi and a low speed fuel outlet leading from the lower portion of said reservoir to the low speed fuel outlet in said mixing chamber and an additional high speed fuel nozzle directly connected with said fuel chamber and discharging into the throat of said small venturi.

14. In a carburetor, having a constant level fuel supply chamber, a main mixing chamber, a small venturi discharging therein, a fuel nozzle discharging into the throat of the small venturi and fed from the said supply chamber, a throttle located in the main mixing chamber on

the downstream side of the outlet from said small venturi and located so as to restrict when closed that portion of the mixing chamber into which the mouth of the small venturi discharges and to divert when partly open the main air flow past said mouth.

15. In a carburetor having a constant level fuel supply chamber, a main mixing chamber of Venturi form, a small venturi discharging into the throat thereof, a fuel nozzle discharging into the small venturi and fed from the said supply chamber, a throttle located in the throat of the main mixing chamber on the downstream side of the outlet from said small venturi and located so as to restrict when closed the said throat into which the mouth of the small venturi discharges and to divert when partly open the main air flow past said mouth.

16. In a carburetor having a constant level fuel supply chamber, a main mixing chamber, a small venturi discharging therein, a fuel nozzle discharging into the throat of the small venturi and fed from the said supply chamber, a butterfly throttle located in the main mixing chamber on the downstream side of the outlet from said small venturi and located so as to restrict when closed that portion of the mixing chamber into which the mouth of the small venturi discharges and to divert when partly open the main air flow past said mouth.

17. In a carburetor having a constant level fuel supply chamber, a main mixing chamber of Venturi form, a small venturi discharging into the throat thereof, a fuel nozzle discharging into the small venturi and fed from the said supply chamber, a butterfly throttle located in the throat of the main mixing chamber on the downstream side of the outlet from said small venturi and located so as to restrict when closed the said throat into which the mouth of the small venturi discharges and to divert when partly open the main air flow past said mouth.

GEORGE M. HOLLEY.

CERTIFICATE OF CORRECTION.

Patent No. 2,080,569.

May 18, 1937.

GEORGE M. HOLLEY.

It is hereby certified that error appears in the printed specification of the above numbered patent requiring correction as follows: Page 5, first column, line 36, for the word "fuel" read constant level fuel supply; and that the said Letters Patent should be read with this correction therein that the same may conform to the record of the case in the Patent Office.

Signed and sealed this 24th day of August, A. D. 1937.

Leslie Frazer

(Seal)

Acting Commissioner of Patents.

chamber adjacent to and above said throttle and air and fuel supply means for said small venturi.

11. A downdraft carburetor as in claim 8 in which the means for discharging high and low speed fuels into said mixing chamber includes a constant level fuel supply chamber, an air vented fuel reservoir associated therewith, a high speed fuel outlet from the upper part of said reservoir and a low speed fuel outlet from the lower part thereof.

12. A downdraft carburetor as set forth in claim 8, in which the means for discharging high speed fuel into said mixing chamber includes a small venturi discharging into said mixing chamber above said throttle, a constant level fuel supply chamber, an air vented fuel reservoir associated therewith, a high speed fuel outlet from the upper part of said reservoir discharging into the throat of said small venturi and an additional high speed fuel nozzle independent of said air vented reservoir but fed from said constant level fuel supply chamber and also discharging into the throat of said small venturi.

13. A downdraft carburetor as set forth in claim 8, in which the means for discharging high and low speed fuel into said mixing chamber includes a small venturi discharging into said mixing chamber above said throttle, a constant level fuel supply chamber, an air vented fuel reservoir associated therewith, a high speed fuel outlet from the upper part of said reservoir discharging into the throat of said small venturi and a low speed fuel outlet leading from the lower portion of said reservoir to the low speed fuel outlet in said mixing chamber and an additional high speed fuel nozzle directly connected with said fuel chamber and discharging into the throat of said small venturi.

14. In a carburetor, having a constant level fuel supply chamber, a main mixing chamber, a small venturi discharging therein, a fuel nozzle discharging into the throat of the small venturi and fed from the said supply chamber, a throttle located in the main mixing chamber on

the downstream side of the outlet from said small venturi and located so as to restrict when closed that portion of the mixing chamber into which the mouth of the small venturi discharges and to divert when partly open the main air flow past said mouth.

15. In a carburetor having a constant level fuel supply chamber, a main mixing chamber of Venturi form, a small venturi discharging into the throat thereof, a fuel nozzle discharging into the small venturi and fed from the said supply chamber, a throttle located in the throat of the main mixing chamber on the downstream side of the outlet from said small venturi and located so as to restrict when closed the said throat into which the mouth of the small venturi discharges and to divert when partly open the main air flow past said mouth.

16. In a carburetor having a constant level fuel supply chamber, a main mixing chamber, a small venturi discharging therein, a fuel nozzle discharging into the throat of the small venturi and fed from the said supply chamber, a butterfly throttle located in the main mixing chamber on the downstream side of the outlet from said small venturi and located so as to restrict when closed that portion of the mixing chamber into which the mouth of the small venturi discharges and to divert when partly open the main air flow past said mouth.

17. In a carburetor having a constant level fuel supply chamber, a main mixing chamber of Venturi form, a small venturi discharging into the throat thereof, a fuel nozzle discharging into the small venturi and fed from the said supply chamber, a butterfly throttle located in the throat of the main mixing chamber on the downstream side of the outlet from said small venturi and located so as to restrict when closed the said throat into which the mouth of the small venturi discharges and to divert when partly open the main air flow past said mouth.

GEORGE M. HOLLEY.

CERTIFICATE OF CORRECTION.

Patent No. 2,080,569.

May 18, 1937.

GEORGE M. HOLLEY.

It is hereby certified that error appears in the printed specification of the above numbered patent requiring correction as follows: Page 5, first column, line 36, for the word "fuel" read constant level fuel supply; and that the said Letters Patent should be read with this correction therein that the same may conform to the record of the case in the Patent Office.

Signed and sealed this 24th day of August, A. D. 1937.

Leslie Frazer
